UNITED STATES PATENT OFFICE.

JOHN ECKERT AND FREDRICK CHARLES LEPPERT, OF SARLES, NORTH DAKOTA.

ATTACHMENT FOR CHURNS.

952,889.

Specification of Letters Patent. Patented Mar. 22, 1910.

Application filed August 6, 1909. Serial No. 511,585.

To all whom it may concern:

Be it known that we, JOHN ECKERT and FRED. C. LEPPERT, citizens of the United States, residing at Sarles, in the county of 5 Cavalier and State of North Dakota, have invented new and useful Improvements in Attachments for Churns, of which the following is a specification.

This invention relates to improvements in 10 dasher attachment for barrel churn, and the object of the invention is to provide a barrel churn adapted to receive either a rotary or an oscillatory motion, with a stationary dasher which is detachably connected with 15 the top of the churn and which is adapted to have its lower arms bear tightly against the inner face of the churn so as to effectively position the dasher within the churn.

With the above, and other objects in view, 20 which will appear as the description progresses, the invention resides in the novel construction of elements hereinafter fully described and claimed.

In the accompanying drawing, there has 25 been illustrated a simple and preferred embodiment of the device, and in which,—

Figure 1 is a perspective view of the dasher. Fig. 2 is a central, longitudinal, sectional view taken through the dasher on the 30 churn. Fig. 3 is a top plan view of the plate connected with the under face of the closure of the churn and to which the dasher is connected.

The improved dasher is adapted to be 35 used in connection with that class of churns known as barrel churning which generally have their sides provided with trunnions adapted to be supported in suitable bearings upon a frame, and whereby the barrel is 40 given either a rotary or an oscillatory movement when the cream within the barrel is being churned.

In the accompanying drawing, the numeral 1 designates the barrel churn of new 45 and preferred formation, being provided with the usual removable top 2 which is secured to the body of the churn in any desired manner. The top 2 has attached to the under face, and arranged centrally there- 50 to, a longitudinal plate 3. The plate 3 may be constructed of wood or any other desired material and is centrally provided with a longitudinal slot or opening 4, provided with a transverse pin 5. The mem- 55 ber 3 is also provided, adjacent its ends, with suitable openings 6, which are adapted

for the reception of threaded elements for securing the device whereby the said plate is rigidly connected with the closure 2.

The numeral 7 designates the dasher. 60 This dasher comprises a central post 8, preferably rounded at its lower extremity, as at 9, and the said post 8 has its upper extremity provided with a hook 10 adapted to engage the pin 5 within the recess 4 of the member 65 3. The post 8 has its body portion substantially square in cross section, and the said post is provided with a plurality of oppositely arranged openings 11, which are adapted for the reception of suitable arms 70 12. By reference to the Figs. 1 and 2 of the drawing, it will be noted that the said arms 12 are each of a different length, the lowermost arm being longer than the remaining arms and this lower arm has its 75 edges beveled to correspond with the inner face of the churn 1 and the said edges are also adapted to tightly engage with the said face of the churn and to force the rounded extremity 9 of the post 8 into engagement 80 with the bottom of the said churn 1.

When it is desired to position the dasher within the churn 1, the said dasher is partly inserted within the churn so as to have its upper portion projecting a suitable distance 85 to provide for the insertion of the hook 10 upon the pin 5 of the member 3. When this is accomplished, the dasher, as well as the member 3 carried by the closure 2, is forced downwardly within the churn until the 90 lower arm 12 tightly engages the inner face of the said churn, as heretofore described.

From the above description, taken in connection with the accompanying drawing, the advantages of construction and method of 95 operation will be apparent to those skilled in the art to which the invention appertains, and while we have illustrated and described the preferred embodiment of the device, as it now appears to us, minor details 100 of construction, within the scope of the following claim, may be resorted to, if desired.

Having thus described the invention, what we claim is:—

In combination with the churn body of 105 the character set forth being provided with a removable closure of a plate centrally secured to the under face of said closure, said plate being centrally provided with a longitudinal recess upon the transverse end, a 110 dasher for the churn, said dasher comprising a central post having a plurality of an-

gularly arranged arms, the lowermost arm being longer than the remaining arms, and adapted to contact the inner face of the churn, and the upper extremity of the post of the dasher being provided with a hook adapted to engage the eye of the plate, substantially as described.

In testimony whereof we affix our signatures in presence of two witnesses.

JOHN ECKERT.

FRED. CHARLES LEPPERT.
